FOLDING LOOP ANTENNA

Filed April 11, 1929 2 Sheets-Sheet 2

UNITED STATES PATENT OFFICE

LLOYD S. BEEBE, OF SCOTIA, NEW YORK, ASSIGNOR TO GENERAL ELECTRIC COMPANY,
A CORPORATION OF NEW YORK

FOLDING LOOP ANTENNA

Application filed April 11, 1929. Serial No. 354,385.

- My invention relates to folding loop antenna structures and it has for one of its objects to provide such a structure which is readily foldable into a small space to permit 5 its being carried about with ease and which is of sufficiently rigid construction to preserve with accuracy the electrical characteristics of the antenna through repeated folding operations.
- 10 For certain purposes for which portable antennæ are employed, and particularly that of measuring field intensity at different points about a common radiating system, it is necessary to employ a loop antenna having 15 a midtap, since by this means, among other reasons, disturbing currents, such as those due to stray capacity effects and the like, which may affect the accuracy of the observation may be caused to produce equal elec- 20 tromotive forces between the midtap and the opposite terminals of the antenna, which electromotive forces may be caused to neutralize each other through suitable circuit connections. It is highly desirable to em- 25 ploy an antenna with a fixed midtap and to provide a folding structure for the antenna of sufficient rigidity to preserve the electrical center of the antenna at the midtap notwithstanding repeated folding of the antenna.
- 30 A further object of my invention is to pro- 35 vide an antenna possessing the above fea- tures and having a frame structure such that the antenna conductor may be wound upon the frame in a continuous solenoid without breaks or interruptions, all of the turns be- 40 ing wound about the frame in parallel rela- tion and equally spaced along the solenoid and all of the turns being of equal length. In this way the antenna may be caused to 45 have a maximum of inductance equally dis- tributed along the solenoid and the two op- posite halves may be made to have equal effects. It is desirable that the two halves of the coil be closely coupled and that the 50 conductors thereof extend in parallel rela- tion since if these conditions do not obtain it may be found that waves traversing the antenna loop will produce different effects in the two halves and thereby affect the accu- racy of the observation.

A further object of the invention is to pro- 55 vide a frame structure having the desired rigidity when extended, and which is char- acterized in that the usual mast is replaced by a small base member, the structure being such that the supporting members of the loop, which are permanently attached to- 60 gether, fall upon each other when the antenna is folded to form a compact column ex- tending in opposite directions from the base member.

A further object of my invention is to pro- 65 vide a folding frame which is practically free from massive flexible or conductive parts, such as may produce non-uniformity in the electrical characteristics of the antenna and which is readily foldable in the manner of a double umbrella into a compact column.

The novel features which I believe to be 70 characteristic of my invention are set forth with particularity in the appended claims. My invention itself, however, may best be understood by reference to the following description taken in connection with the ac- 75 companying drawings in which Fig. 1 repre- 80 sents my antenna in its extended condition; Fig. 2 represents my antenna in its partially folded condition, and Fig. 3 represents the antenna completely folded.

Referring to Fig. 1 of the drawings it will be seen that the antenna structure 1 comprises a loop conductor wound in a poly- 85 gonal solenoid formation upon conductor carrying members 2, one of which is located at each vertex of the polygon, and all of which are supported in parallel relation from the hub structure. The hub structure com- 90 prises a pair of members 3 and 3' which are arranged side by side at the central portion of the antenna. Hingedly connected to the member 3 are a plurality of supports 4 which extend radially from the central member to one end of each of the different conductor carrying members 2, these supporting mem- 95 bers being likewise hingedly connected to the conductor carrying members. Similarly the central member 3' has hingedly connected thereto a plurality of supports 5 which extend parallel with the supports 4 and are likewise 100

hingedly connected to the opposite end of the conductor carrying members 2.

The supporting members 4 and 5 which are connected to a conductor carrying member 2 are hingedly connected thereto for outward movement and are secured against inward movement by means of straps 3. These straps constitute braces between the respective supporting members and the carrying member, and are suitably suspended from the bolt which extends through each of the bifurcated end portions of the carrying members and the end of the corresponding supporting member thereby to constitute a pivot or hinge, by means of which the supporting member is attached to the carrying member. Similarly the members 4 and 5 are hingedly attached to the respective central members for inward movement and are secured against outward movement by braces 6, one of which is attached to the outer surface of each of the supports 4 and 5 and extend beyond the inner end thereof to engage the outer surface of the central member. By means of the straps 7 and braces 6 any sidewise movement or swaying of any portion of the loop is avoided.

The central members 3 and 3' are locked together by means of a bayonet joint which is best shown in Fig. 2, this joint comprising a socket member 8 which is attached to the central member 3 and a member 8' which projects from the central member 3' to cooperate with the socket member 8. A tooth 9 projects from the member 8' and is arranged to cooperate with an opening 10 in the socket member 8, thereby to lock the central members 3 and 3' in fixed spaced relation. Either or both of the members 8 and 8' may be made rotatable in order to provide for locking and unlocking of the central members.

The conductor 1 is wound upon the carrying members 2 from one side of the carrying members as at the terminal 11 progressively across the carrying members turn by turn to the opposite terminal member 12. Thus the antenna comprises a uniform solenoid extending across the carrying members. The conductor is secured to each carrying member by means of strips 13 which are attached as by means of screws to the outer surface of the carrying members to securely clamp the conductors between the strips and the conductor carrying members. A midtap may be provided upon the center turn of the loop as at 14.

It will thus be seen that all of the turns of the conductor are of the same length and are parallel, that the two halves of the antenna are electrical equivalents, and that the electrical center of the antenna may be maintained at the tap 14. The supports 4 and 5 are rigid thereby firmly to hold the loop in shape when it is extended and are sufficiently light to obviate non-uniformity resulting

from massive material located within the field of the antenna. These members and similarly the hub structure and carrying members 3 are comprised of suitable non-conducting material such as wood or a phenolic condensation product.

To fold the antenna it is preferable, to avoid entangling and kinking of the wires, to place it in a horizontal position, as shown in Fig. 2, and then to unlock and separate the central members as by grasping the knobs 15 and 15' and pulling them outwardly. The supporting members 4 and 5 then fall upon each other into a column extending between the central members 3 and 3', as shown in Fig. 3, the carrying members extending in the direction of the column at the middle portion thereof. The conductors then fall in loose loops fixed at the middle of the column and suspended loosely along the column toward the central members. Preferably the conductor 1 is multiple strand to provide a degree of flexibility such as to prevent the conductor from assuming a definite set, kinks, etc. when folded.

For the purpose of supporting the antenna structure a suitable base member 16 is attached to one of the members 13. In this way any interruption of the continuity of the loops and any loose coupling between the two halves of the loop which may result from separating the conductors sufficiently to permit the use of a mast projecting between the conductors is avoided.

While I have shown a particular embodiment of my invention, it will of course be understood that various modifications may be made, and I intend by the appended claims to cover any such modifications as fall within the true spirit and scope of my invention.

What I claim as new and desire to secure by Letters Patent of the United States is:

1. A folding antenna structure, comprising a pair of central members arranged side by side, a plurality of conductor carrying members, means attached to the central members for supporting said conductor carrying members about the central members in parallel relation, a loop conductor wound upon said carrying members to form a solenoid, and means cooperating with the central members to cause the supporting means to fall into a column extending from the carrying members outward in opposite directions toward the central members when the central members are separated.

2. A folding antenna structure, comprising a pair of central members arranged side by side, a plurality of conductor carrying members, a loop conductor carried by said members, a plurality of supporting members extending radially from each of said central members, each of said supporting members being hingedly connected to the respective central member and to one of said carrying

members, and each carrying member being supported by a radial member extending from each central member, whereby said central members may be separated causing the supporting members to fall upon each other to form a column extending between the two central members.

3. A folding antenna frame, comprising a hub structure, a plurality of conductor carrying members arranged about said hub structure, a pair of supporting members extending between opposite points on each of said carrying members and said hub structure and hingedly connected to said carrying members for outward movement, said supporting members being rigidly secured to each other by said hub structure, and detaching means at the hub structure whereby the supporting members connected to opposite points on the carrying members are movable outward thereby to cause said supporting and carrying members to fall upon each other in a column.

4. A folding antenna structure, comprising a pair of central members arranged side by side, a plurality of conductor carrying members, a loop conductor carried by said members, a plurality of supporting members extending radially from each of said central members to said carrying members, each carrying member being supported by a supporting member attached to each of said central members, each supporting member being hingedly attached to the carrying member for outward movement from the normal position and secured against inward movement therefrom, and attached to the central member for inward movement from the normal position and secured against outward movement therefrom whereby said central members may be separated causing said supporting members to fall in a column between the central members.

5. A folding antenna structure, comprising a pair of central members arranged side by side, a plurality of conductor carrying members, a loop conductor carried by said members, a plurality of supporting members extending radially from each of said central members, each of said supporting members being hingedly connected to the respective central member and to one of said carrying members, and each carrying member being supported by a radial member extending from each central member, whereby said central members may be separated causing the supporting members to fall upon each other to form a column extending between the two central members, spacing means between said central members comprising a socket attached to one member and a projecting member secured to the other member and arranged to cooperate with said socket to secure said members together in fixed space relation, whereby when said

central members are separated said supporting members fall upon each other to form a column extending between the central members.

In witness whereof, I have hereunto set my hand, this 10th day of April, 1929.

LLOYD S. BEEBE.
